CLAIM

The ornamental design for a two wheeled board, as shown and described.

DESCRIPTION

FIG. 1 is a front, top, left-side perspective view of a two wheeled board of our design.

FIG. 2 is a partial detailed view of the ornamentation on the front of the board in FIG. 1;

FIG. 3 is a rear, bottom, left-side perspective view of FIG. 1;

FIG. 4 is a top view of FIG. 1;

FIG. 5 is a bottom view of FIG. 1;

FIG. 6 is a front view of FIG. 1;

FIG. 7 is a partial detailed view of the ornamentation on the front of the board in FIG. 6;

FIG. 8 is a rear view of FIG. 1;

FIG. 9 is a left-side view of FIG. 1; and,

FIG. 10 is a right-side view of FIG. 1.

Broken lines are used to illustrate portions of the two wheeled board that form no part of the claimed design.
